(**) Term: **14 Years**

(21) Appl. No.: **29/449,200**

(57) **CLAIM**

I claim, the ornamental design for an exterior surface configuration of a vehicle lamp, as shown and described.

(22) Filed: **Mar. 14, 2013**

DESCRIPTION

(51) **LOC (9) Cl.** **26-06**

FIG. 1 is a perspective view of an exterior surface configuration of a vehicle lamp showing my present design;

(52) **U.S. Cl.**

FIG. 2 is a front view thereof;

USPC **D26/28**

FIG. 3 is a right view thereof; and,

(58) **Field of Classification Search**

FIG. 4 is a top plan view thereof.

USPC D26/28-36; 362/459-468, 475-478,
362/485-487

The broken line showing of the front edge portion of the vehicle is included for the purpose of illustrating only and forms no part of the claimed design.

See application file for complete search history.
